UNITED STATES PATENT OFFICE.

PASQUALE GILIBERTI, OF NEW YORK, N. Y.

DRIVING MECHANISM.

1,262,772.

Specification of Letters Patent. Patented Apr. 16, 1918.

Application filed June 12, 1917. Serial No. 174,243.

To all whom it may concern:

Be it known that I, PASQUALE GILIBERTI, a citizen of the United States, and resident of New York city, borough of the Bronx, in the county of the Bronx and State of New York, have invented certain new and useful Improvements in Driving Mechanism, of which the following is a specification.

The object of my invention is to provide a driving mechanism, comprising a rockable or reciprocative lever and a driven member, whereby said member may be rotated continuously in one direction by means of the to and fro movements of said levers, and whereby by a simple adjustment of the parts said member may be driven in the reverse direction by similar to and fro movements of said lever.

My invention is adapted to be utilized for operating the drive wheel or wheels of a child's wagon or vehicle for propelling the latter, and is also adapted to be utilized in a boat for operating a propeller of the latter, and in other relations.

My invention comprises novel details of improvement and combinations of parts that will be more fully hereinafter set forth and then pointed out in the claims.

Reference is to be had to the accompanying drawings forming part hereof, wherein,

Figure 1 is a plan view illustrating my improvements embodied in a child's wagon; Fig. 2 is a detail view of part of my improved driving mechanism; Fig. 2^a is a detail view of part of Fig. 2; Figs. 3 and 4 are enlarged views of the operating lever and driving gears of Fig. 6; Fig. 5 is a view illustrating a boat equipped with my improvements; and Fig. 6 is an enlarged plan view illustrating my improvements adapted for propelling the boat.

Similar numerals of reference indicate corresponding parts in the several views.

The letters A, B indicate driving gears that are spaced apart and mounted to rotate upon a shaft or rod P supported in bearings upon a frame W or in a boat X. A lever indicated generally at D is journaled at its inner end to rock on shaft P and is shown comprising two spaced side members d shown having a block e secured therebetween at the outer end uniting the members d securely together. Lever D is shown between gears A,

B. The gear wheels A, B are provided with ratchet teeth E, E' which face and operate in opposite directions. The lever D is provided with pawls O, O' respectively adapted to engage ratchets E, E', whereby when lever D is moved in one direction wheel A will be rotated in the same direction, and when said lever is moved in the opposite direction wheel B will be rotated in such direction. A driven member G, shown in the form of a shaft, is provided with a pinion F interposed between and meshing with the gears A, B, whereby when lever D is rocked to and fro said pinion and member will be rotated in a given direction by said pawls and driving gears, the pawls slipping freely over the corresponding ratchets when moved reversely. In order to rotate member G in a direction reverse to its direction of rotation from the pawls O, O', I provide teeth 8, 8' carried by the wheels A, B respectively, and which face in the direction reverse to the associate ratchet teeth E, E', and pawls 7, 7' are adapted to coöperate with ratchet teeth 8, 8' respectively. Said pawls are movably carried by lever D, and are shown slidably supported in holes d' in members d of lever D, springs 6, 6' being shown secured to said members d and pawls 7, 7' normally tending to withdraw said pawls from the corresponding ratchet teeth 8, 8'. A rod 4 is slidably carried by lever D, being shown slidably in holes in cross bars d², secured between the members d. Rod 4 is shown provided with pawl operating members 5, 5' which are adapted to pass between the springs 6, 6' to engage the latter to push them with the pawls 7, 7', whereby said pawls will be moved into engagement with the corresponding teeth 8, 8'. Levers 1, 2, are pivotally connected with rod 4 at 3, and said levers co-operate with members d, d of lever D, being shown operative in openings a in said members (Fig. 2), although said levers may be otherwise pivotally connected with lever D. The pawls O, O' are pivotally carried by lever D, as at o, and are shown connected by wires 9, 9' with the levers 1, 2, respectively. The rod 4 is shown provided with a projection 4^a adapted to enter one or another of the notches 10 in lever D to retain said rod set in adjusted position.

The arrangement described is such that

when levers 1, 2, are in positions shown in Figs. 1 and 2 the pawls O, O' will coöperate with the ratchet E, E' for causing rotation of driving gears A, B and the consequent rotation of pinion F and driven member G in one direction, when lever D is rocked to and fro. When lever 1 is operated, as by raising its end in Fig. 1, the rod 4 will be pushed toward axle P, whereupon lever 2 will be moved corresponding to the movement of lever 1, the connections 9, 9' will withdraw pawls O, O' from ratchets E, E' and the members 5, by sliding between the springs 6, 6' will spread the latter and thereby push the pawls 7, 7' into coöperation with ratchets 8, 8', whereby when lever D is rocked the gears A, B will be rotated in the direction reverse to that caused by the pawls O, O' and the pinion F and driven member G will likewise be continuously rotated in a correspondingly reverse direction to that previously described. It thus will be understood that the driven member G may be rotated continuously in one or another direction during rocking movements of lever D, according to whether the pawls O, O' operate the ratchet E, E' or the pawls 7, 7' operate the ratchets 8, 8', the change of direction of rotation of member G being accomplished by shifting the levers 1, 2, from one position to another to correspondingly shift the coöperative relation of the pairs of pawls with their corresponding ratchets, the rocking movements of lever D being the same for either direction of rotation of member G.

While my improvements may be used for various purposes, I have illustrated them as installed in a child's wagon in Fig. 1, wherein the drive shaft M is provided with a pinion L secured thereto and in mesh with a pinion C secured upon driven member G, one or both of the companion wheels R being secured to said shaft. The other pair of wheels R may be steered by any suitable means in an ordinary manner. With a wagon equipped with my improvements as described, the child may rock the lever D back and forth, and when the pawls O, O' operate the gears A, B the drive wheel R will cause the wagon to proceed in one direction, as forwardly, and when the levers 1, 2, are shifted the pawls O, O' will cease to operate the gears A, B and the pawls 7, 7' will operate said gears but in a reverse direction to that last described, whereby the drive wheel and the wagon will be caused to operate reversely.

In the arrangement shown in Figs. 5 and 6 my improvements are applied in a boat, and the propeller C² is substituted for the driving pinion C of Fig. 1, upon the driven member G, the pinion L and its shaft and roadwheel being omitted. The propeller C² will be operated in one direction by the re-

ciprocations of lever D by means of the corresponding rotation of member G derived through pawls O, O', for propelling the boat, say forwardly, and when it is desired to drive the boat backwardly the levers 1, 2, 70 will be appropriately shifted to cause shifting of the pairs of pawls in manner before described, and continued reciprocation of lever D will cause reverse operation of the propeller through pawls 7, 7'. 75

It will be understood that with the driving mechanism described the driven member G may continue to rotate in a given direction when lever D is brought to rest, so as to permit the wagon to coast or the propeller to continue to rotate freely, since the operating ratchets may continue to rotate in the direction of previous propulsion under their corresponding pawls. 80

While I have illustrated and described a particular embodiment of my invention, it will be understood that the same is not limited to the particular arrangements and relations of parts set forth, as the same may be varied, within the scope of the appended 90 claims, without departing from the spirit of the invention.

Having now described my invention what I claim is:—

1. The combination of a pair of driving 95 gears, a pinion in mesh therewith, a driven member operated by said pinion, a lever, each of said driving gears having a pair of ratchets facing in opposite directions, a pair of pawls carried by said lever for one of the 100 ratchets of said gear, another pair of pawls carried by said lever for the other ratchets of said gears, levers operatively carried by said first named lever and respectively connected with the first named pawls to release 105 them from their ratchets, a rod operatively connected with said pair of levers, and guided upon the first named lever, said rod having means to push the second named pawls into coaction with their ratchets when 110 said pair of levers remove the first named pawls from their ratchets, and vice versa.

2. The combination of a pair of driving 115 gears, a pinion in mesh therewith, a driven member operated by said pinion, a lever, each of said driving gears having a pair of ratchets facing in opposite directions, a pair of pawls carried by said lever for one of the 120 ratchets of each gear, another pair of pawls carried by said lever for the other ratchets of said gears, levers operatively carried by said first named lever and respectively connected with the first named pawls to release them from their ratchets, 125 springs connected with the last named pawls, means movably supporting said pawls upon said lever, a pair of levers operatively carried by said first named lever and operatively connected with the first named pawls to release them from their ratchets, a rod 130

operatively connected with said pair of levers, means guiding said rod upon the first named lever between the second named pawls, and spring members carried by said 5 rod to coöperate with the first named springs and pawls to push the latter into coaction with their ratchets when the pair of levers

are operated to release the first named pawls from their ratchets, and vice versa.

Signed at New York city, in the county 10 of New York, and State of New York, this 11th day of June, 1917.

PASQUALE GILIBERTI.
